EXPANSIBLE LINK CHAIN FOR A WRIST-
BAND OR SIMILAR ARTICLEAlfred Pinson, Stamford, Conn., assignor to Apex
Accessories Co., Inc., Greenwich, Conn.

Application February 27, 1953, Serial No. 23,818

Term of patent 14 years

(Cl. D45—4)

To all whom it may concern:

Be it known that I, Alfred Pinson, a citizen of the United States, residing at Stamford, in Fairfield County, State of Connecticut, have invented a new, original, and ornamental Design for an Expansible Link Chain for a Wrist Band or Similar Article, of which the following is a specification, reference being had to the accompanying drawing, forming part thereof.

Fig. 1 is a plan view of an expansible link chain showing my new design, the conventional bottom links being shown in broken lines;

Fig. 2 is a side elevational view thereof;

Fig. 3 is a side elevational view of the inner face of one of the border top links of Fig. 1; and

Fig. 4 is an end elevational view of the top link shown in Fig. 3.

I claim:

The ornamental design for an expansible link chain for a wrist band or similar article, as shown and described.

ALFRED PINSON.
